UNITED STATES PATENT OFFICE.

CARL HORIX, OF CHICAGO, ILLINOIS.

DESIGN FOR A PEN SUPPORT.

Application filed March 18, 1927. Serial No. 21,183. Term of patent 7 years.

To all whom it may concern:

Be it known that I, CARL HORIX, a citizen of the United States, residing at Chicago, in the county of Cook and State of Illinois, have invented a new, original, and ornamental Design for a Pen Support, of which the following is a specification, reference being made to the accompanying drawing, forming a part thereof.

In the drawing—

The figure is a perspective view of a pen support showing my new design.

I claim:—

The ornamental design for a pen support, as shown.

Chicago, Illinois, March 8, 1927.

CARL HORIX.
